US0D1088849S

(12) **United States Design Patent** (10) **Patent No.:** **US D1,088,849 S**
(45) **Date of Patent:** **** Aug. 19, 2025**

(54) **GRAB HANDLE FLANGE**

(71) Applicant: **F&V Corporation**, Independence, OH (US)

(72) Inventors: **Ryan Alan Lally Fry**, Perrysburg, OH (US); **James Charles Varner**, Independence, OH (US); **Declan Palmer**, Dongguan (CN); **David Wilhelm**, Perrysburg, OH (US)

(73) Assignee: **F&V Corporation**, Independence, OH (US)

(**) Term: **15 Years**

(21) Appl. No.: **29/911,753**

(22) Filed: **Sep. 8, 2023**

(51) LOC (15) Cl. **08-08**

(52) U.S. Cl.

USPC **D8/382**; D8/29

(57) **CLAIM**

The ornamental design for a grab handle flange as shown and described.

DESCRIPTION

FIG. 1 is a top perspective view of a grab handle flange showing our new design;

FIG. 2 is a bottom perspective view thereof;

FIG. 3 is a first side view thereof;

FIG. 4 is a second side view thereof;

FIG. 5 is a top view thereof;

FIG. 6 is a bottom view thereof;

FIG. 7 is a third side view thereof;

FIG. 8 is a fourth side view thereof;

FIG. 9 is a top perspective view of another embodiment of a grab handle flange showing our new design;

FIG. 10 is a bottom perspective view thereof;

FIG. 11 is a first side view thereof;

FIG. 12 is a second side view thereof;

FIG. 13 is a top view thereof;

FIG. 14 is a bottom view thereof;

FIG. 15 is a third side view thereof; and,

FIG. 16 is a fourth side view thereof.

(Continued)

The broken lines in the drawings are included to show portions of the grab handle flange that form no part of the claimed design.

1 Claim, 6 Drawing Sheets
